UNITED STATES PATENT OFFICE.

FRANK RILEY, OF NEW YORK, N. Y.

TURNED SHOE.

1,158,853.

Specification of Letters Patent. Patented Nov. 2, 1915.

Application filed February 25, 1914. Serial No. 820,944.

To all whom it may concern:

Be it known that I, FRANK RILEY, a citizen of the United States, and a resident of the borough of Manhattan, city, county, and State of New York, have invented certain new and useful Improvements in Turned Shoes, of which the following is a specification.

This invention relates to improvements in turned shoes.

By the use of my invention I am enabled to produce, first, a turned shoe having a shank piece provided with a rigid arch-supporting body or shank portion and an integral forwardly-extending sole covering portion or sock lining of reduced thickness, whereby such turned shoe is provided with the usual stiff arch-supporting shank; a proper lasting support for the heel; and the stitches and other roughened parts of the sole are covered to provide a smooth surface and a sole cushion may be provided without materially detracting from the flexibility which characterizes turned shoes; furthermore, the heel nails and lasting tacks may be clenched below the upper surface of the heel seat portion of such combined shank piece and sock lining, the said heel seat portion of the shank piece being sliced and provided with a split intermediate its flesh and grain surfaces, extending parallel thereto for that purpose, thus also affording a smooth even and flush surface at said heel seat, and permitting the insertion in said split of a heel cushion of felt or other suitable material, thus enabling the production of a turned shoe having both a cushioned sole and a cushioned heel, where cushioning is most desirable, and at the same time providing a rigid and solid shank or arch support, the whole being inexpensive of manufacture.

I will now describe my preferred form of shoe and then point out the novel features in claims.

In the accompanying drawings in which similar reference characters designate corresponding parts throughout the several views, Figure 1 is a perspective view of a turned shoe embodying my invention after the same is turned and before the application of my novel combined shank piece and sock lining with nailless heel seat; Fig. 2 is a side elevation partly in longitudinal section of a shoe illustrating my combined shank piece having an integral sock lining

and nailless heel seat in place in conjunction with suitable cushions; Fig. 3 is a section on the line 3—3 of Fig. 2; Fig. 4 illustrates in perspective a view of a sole cushion adapted to be inserted between the reduced front portion of my integral shank piece and sock lining and the sole proper; Fig. 5 is a perspective view showing my shank piece with an integral sock lining and nailless heel seat; Fig. 6 is a view in perspective of a heel cushion adapted to be inserted in the split of the heel seat; Fig. 7 is a longitudinal side elevation of said shank piece; and Fig. 8 is a section on the line 8—8 of Fig. 5.

Referring now to the accompanying drawings, 1 illustrates the upper leather of a turned shoe, 2 the sole portion thereof, which are sewn together by stitches 3 in inverted position and then turned into the normal position shown in Fig. 1, the heel portions of the upper and sole leathers being left unsewn as shown in said Fig. 1. The said heel portion of the shoe is then lasted to a combined shank piece and sock lining 4 which, as shown, is provided at the heel portion with a split 5, preferably formed by slicing the heel seat portion of said shank piece intermediate the outer or flesh and upper or grain sides thereof and parallel with such surfaces to an extent substantially equal to the size of the heel so as to include the entire area through which metallic fastening or lasting devices, such as lasting tacks, slugs and heel nails, are usually driven, thus forming a nail covering scarf 6 and a nail clenching body 7 to which the upper leather, heel portion of the sole and heel 8 are fastened or lasted by means of nails and the like.

My preferred method of attaching the heel, sole and heel portion of the upper leather, is to take a suitable plate of metal or other material impenetrable to such fastening devices, insert the same in the split 5 between the scarf 6 and body 7, then last the upper leathers to the body portion 7 of the shank piece by means of lasting tacks 9 which are clenched against the lower surface of said impenetrable plate and retain the parts firmly together; the sole is then lasted to said body portion 7 by means of slugs 10, also clenched against said impenetrable plate on the upper surface of the body portion 7, and the heel is secured in place by means of heel nails 11, likewise

clenched against said plate on the upper surface of the body portion 7, the top layer 8^a of the heel being subsequently applied to the heel by means of tacks 11^a. The impene-
5 trable plate is then preferably withdrawn and a heel cushion of felt or other suitable material, such as illustrated by the numeral 12 is inserted and cemented in place and the scarf 6 is turned down and also cemented
10 in place.

The shank piece 4 is provided with a forward sole covering extension 13 which is preferably reduced by skiving or shaving the bottom side of the same forwardly from
15 a line substantially coincident with the sole bend, and to this reduced portion, preferably before the shank piece is lasted to the heel as hereinabove described, is suitably cemented or otherwise secured a cushion 14
20 of cork, felt or other suitable material which cushion compensates for the portion removed as aforesaid and the said shank piece with its integral sole-covering extension carrying said cushion is cemented in place over
25 the stitches 3. The said shank piece is also preferably reduced at the side edges as shown at 13^a—13^a to compensate for the raised surface due to stitching 3.

It will be seen from the above that I am
30 enabled to produce a shoe which may be provided with a cushion heel, a rigid arch supporting shank portion, and a cushioned sole portion, while at the same time and by a single piece, eliminating or covering the
35 roughened surfaces due to the lasting of the heel as well as the roughened surfaces due to the stitching of the sole. Furthermore I am enabled to insert a sole cushion of cork so as to prevent moisture from reaching
40 the foot which will cover the entire surface of the fore part of the sole or I may insert a cushion of felt if desired. Furthermore, the sides of the front portion of the upper contiguous to the stitching will be reinforced
45 and compelled to retain their shape, all sagging which is common at this point in turned shoes, being avoided. Furthermore the advantages above enumerated may be produced in a workmanlike and inexpensive
50 manner and substantially all the usual elasticity of a turned shoe may be retained while many of the advantages of a welt shoe will be procured without the expense and multiplicity of operations necessarily incident to the latter.

In order to retain the inside appearance of the ordinary turned shoe at present used, I preferably stain that portion of the shank piece which lies back of a line 15 extending across the shank piece from one side to the other.

Having described my invention, I claim:

1. A turned shoe comprising an outsole, an upper, and an insole, said insole comprising a rigid shank portion of suitable thickness, and an integral portion of relatively thin material extending forwardly from said shank portion and covering the stitching along the marginal edges of the forepart of the outsole. 70

2. A turned shoe, comprising an outsole, an upper, an insole, said insole comprising a rigid shank portion, a portion of reduced thickness extending forwardly from said shank portion and covering the forepart of 75 the outsole and a heel seat portion provided with a split intermediate its flesh and grain surfaces extending parallel thereto, and metallic fastening devices securing the heel parts of said shoe together and cemented within said split. 80

3. A turned shoe, comprising an outsole, an upper, an insole, said insole comprising a rigid shank portion, a portion of reduced thickness extending forwardly from said 85 shank portion and covering the forepart of the outsole, and a cushion inserted between the said reduced portion and said outsole.

4. A turned shoe, comprising an outsole, an upper, an insole, said insole comprising a rigid shank portion, a portion of reduced thickness extending forwardly from said shank portion and covering the forepart of the outsole, a cushion inserted between the reduced portion and said outsole and cemented in place, a heel seat portion provided with a split intermediate its flesh and grain surfaces extending parallel thereto, a cushion inserted in said split and cemented in place and metallic fastening devices securing the heel parts of said shoe together and cemented within said split. 95 100

In witness whereof, I have signed my name to the foregoing specification in the presence of two subscribing witnesses.

FRANK RILEY.
